UNITED STATES PATENT OFFICE.

HARRY J. CRINER, OF MOLINE, ILLINOIS, ASSIGNOR TO D. M. SECHLER IMPLEMENT & CARRIAGE COMPANY, OF MOLINE, ILLINOIS, A CORPORATION OF ILLINOIS.

WASHING-MACHINE.

1,364,079.

Specification of Letters Patent.

Patented Jan. 4, 1921.

Application filed May 3, 1920. Serial No. 378,449.

To all whom it may concern:

Be it known that I, HARRY J. CRINER, a citizen of the United States, and a resident of Moline, in the county of Rock Island and 5 State of Illinois, have invented certain new and useful Improvements in Washing-Machines, of which the following is a specification, reference being had to the accompanying drawings.

10 My invention relates to washing machines, and it has for its object the provision of a new and improved form and arrangement of the parts by which a wringer is driven in various adjusted positions with respect to 15 the machine as a whole, and by which the adjustment of the position of the wringer is accomplished, means being provided for preventing the driving of the wringer during the process of adjustment. The preferred means by which I have accomplished 20 my object are illustrated in the drawings and are hereinafter described. That which I believe to be new and desire to cover by this application is set forth in the claims.

25 In the drawings,—

Figure 1 is a side view of a washing machine embodying my improvements, a portion of the wringer being broken away;

20 Figs. 2, 3 and 4 are diagrammatic views illustrating three of the several different positions of the wringer;

Fig. 5 is an enlarged detail of the driving mechanism for the wringer, being substantially a section taken on line 5—5 of Fig. 4;

30 Fig. 6 is a horizontal section taken on line 6—6 of Fig. 5; and

Fig. 7 is substantially a horizontal section taken on line 7—7 of Fig. 5.

Referring to the several figures of the 40 drawings in which corresponding parts are indicated by the same reference characters,—

10 indicates the body of my improved washing machine mounted upon casters 11 45 of any suitable type and closed at its upper end by a cover plate 12. A drum 13 of any approved construction is revolvably mounted between the side walls of the machine, being driven by any suitable train of mechanism, not illustrated in detail, from a vertical shaft 14 journaled in a vertical cylindrical casing 15 at one corner of the machine. The shaft 14 is provided with a worm gear 16 which is driven by a worm 50 55 17 mounted upon a horizontal shaft 18 which

in turn is driven by a motor 19 through the medium of a belt 20 and pulleys 21 and 22. The train of mechanism for driving the drum 13 from the shaft 14 comprises a throw-out mechanism of any suitable type 60 adapted to be thrown into and out of operation by means of a lever 23.

Referring now particularly to Fig. 5, 24 indicates a housing provided with a stud 25 depending from its lower face and extending into the upper end of the casing 15 in which it has a working fit. A horizontal bearing is provided between the stud and the casing by means of flanges 26 and 27 on such parts respectively, whereby the housing 24 is supported very firmly and strongly in position so as to be revoluble about a vertical axis thereon. As is clearly shown in this figure, the stud 25 furnishes a bearing for the upper end of the shaft 14. 70

At one end portion, the housing 24 is provided with another stud 28 upon the outer end of which is secured the framework 29 of a wringer of any approved type, the connection being effected by means of 80 bolts through a flange 30 on the outer end of the stud 28. In the construction shown the wringer comprises co-operating rollers 31, 32 of any approved type mounted upon shafts 33 and 34, respectively, which are 85 operatively connected together by means of the ordinary intermeshing gears 35 and 36. As is clearly shown in Fig. 5, the shaft 34 upon which the roller 32 is mounted extends 90 outward into the housing 24 within which it is provided with a sleeve 37 which is feathered thereon so as to be rotated thereby but slidable longitudinally thereof. The sleeve 37 is provided with bevel gears 38 and 39 fixed thereon, in the construction 95 shown being formed integrally therewith. The bevel gears 38 and 39 are spaced apart in such relation as to stand on opposite sides of a bevel gear 40 secured upon the upper end of the shaft 14, the spacing being such 100 that the gears 38 and 39 are adapted to stand clear of the gear 40 and such that when desired either gear 38 or 39 is adapted to be moved into operative engagement with the gear 40. For shifting the gears 38 and 39 a lever 41 is provided pivotally mounted upon a pin 42. The lower end of the lever 41 is bifurcated, the lower ends of the arms having operative engagement with a circumferential groove 43 about the sleeve 37. 110

105

- As will be appreciated by an inspection of Fig. 5, the rollers 31 and 32 of the wringer are adapted to remain idle while the gears 38 and 39 stand in the position shown in Fig. 5; are adapted to be driven in one direction when the gear 38 is thrown into mesh with the gear 40; and are adapted to be driven in the opposite direction when the gear 39 is thrown into mesh with the gear 40. Any suitable means as may be desired may be provided for holding the lever 41 releasably in its several operative positions for assuring continued meshing of the gears.
- By the use of the means above described comprising the housing 24 with its lugs or studs 25 and 28 for supporting the wringer structure, the wringer is adapted to be swung horizontally into any desired position with respect to the washing machine. For holding the wringer in any one of a plurality of desired positions with respect to the machine, I have provided a movable latch in the form of a lever 44 pivotally mounted upon a pin 45 carried by suitable lugs 46 projecting laterally from the stud 25. The turned end 47 of the lever 44 extends into a notch 48 in the flange 26 and in its normal position as shown in dotted lines in Fig. 5 extends also into one of the notches 49 in the flange 27, serving to hold the shaft-casing 24 against rotation with respect to the housing 15, in the construction shown four of the notches 49 being provided. As will be appreciated from an inspection of Fig. 5, when the lever 44 is moved upward into the position shown in solid lines in that figure, the turned end 47 clears the notches 49 of the flange 27 so as to permit the horizontal swinging movement of the wringer with respect to the machine.
- Means is also provided for preventing an upward movement of the lever 44 into the position shown in solid lines in Fig. 5 while either of the gears 38 or 39 is in operative engagement with the gear 40. This feature is very important. If the lever 44 were raised out of its locking position with the gear 40 in engagement with either of the gears 38 or 39, the power applied through the gear 40 would be adapted to do either of two things,—namely, to drive the rollers 31 and 32 of the wringer in the normal manner, or to swing the wringer as a whole about its vertical axis. If the wringer should be swung in this manner through the power applied at the gear 40, the rollers 31 and 32 would not at the same time be driven positively. When, however, the wringer was brought into contact with something which would prevent its swinging farther, in that case the power would immediately be applied to the rollers 31 and 32. If it happened to be the fingers of the operator

which had served as the obstruction for preventing the further swinging of the wringer by reason of the fingers coming in contact with the idle rollers, the immediately subsequent application of power to the rollers would be a very serious matter, probably resulting in a serious injury to the operator. This safety means comprises a pin or plunger 50 slidably mounted in an appropriate wall portion of the housing 24 between the sleeve 37 and the lever 44. A circumferential groove 51 is provided in the sleeve 37 in such position as to be in alignment with the pin 50 when the sleeve 37 is in such position as to hold the gears 38 and 39 both out of engagement with the gear 40. The pin 50 is of such a length that the lever 44 cannot be moved sufficiently to clear the notch 49 of the flange 27 except when the pin 50 is displaced upward within the groove 51. It is thus clear that the lever 44 cannot be given a complete operative movement for effecting an adjustment of the position of the wringer except when the gears 38 and 39 are held by the pin 50 in their neutral position with respect to the gear 40. In the construction shown, the pin 50 is held yieldingly downward by means of a spring 52 which engages at its lower end a key 53 carried by the pin. With the washing machine 10 in position adjacent to one of two stationary tubs 54 and 55, the wringer is adapted to be swung into the position shown in Fig. 2 so as to wring the clothes from the washing machine to the tub 54 which would preferably contain rinsing water. The wringer can then be swung to the position shown in Fig. 3 to wring the clothes from the tub 54 to the tub 55 which might contain a second rinsing water or a bluing water as might be desired. After the clothes have been wrung into the tub 55, the wringer may be shifted into the position shown in Fig. 4, so as to wring the clothes from the tub 55 into a clothes basket 56 or to any other suitable container. If it is desired to wring the clothes directly from the washing machine 10 to a clothes basket or other container in the position occupied by the clothes basket in Fig. 4, this can be accomplished by shifting the wringer 90° in clockwise direction, as illustrated in Fig. 4, so as to stand above the side of the washer, the direction of rotation of the rollers 31 and 32 being changed to correspond to the direction in which the clothes are to travel.

What I claim as my invention and desire to secure by Letters Patent, is—

1. The combination of a support, a wringer revolvably mounted thereon so as to swing horizontally thereabout, movable means for locking said wringer against swinging, a driving gear, a sleeve slidably mounted adjacent to said driving gear, a

- second gear mounted on said sleeve and adapted to be moved into operative engagement with said first-named gear, a circumferential groove being formed in said sleeve, 5 and a plunger radially-positioned with respect to said sleeve and adapted to engage said groove and in that position to permit an operative stroke of said locking means for permitting the swinging of the wringer, 10 said plunger being adapted when engaging the periphery of the sleeve to prevent a swinging movement of the wringer, the groove being positioned upon the sleeve to receive the plunger only when said two 15 gears are out of engagement with each other.
2. A machine of the class described comprising in combination a body, a gear-housing rotatably connected therewith so as to 20 swing about a vertical axis, a horizontal
- shaft in said housing, gearing in said housing comprising a driving member and a driven member, the latter being mounted on a longitudinally-movable sleeve on said shaft, said sleeve being provided with a circumferential groove, a pivoted latch connected with the gear-housing and adapted to engage registering notches formed respectively in a stationary member connected to said body and in a member connected 25 with said rotatable gear-housing, a spring-pressed pin normally holding said latch in said notches to lock the gear-housing against rotation, and means for shifting said driven member out of mesh with said driving member and at the same time bringing the groove in said sleeve opposite said pin to permit said pin to move away from said latch. 30 35

HARRY J. CRINER.
